R. E. GOLDSBROUGH

BURNER FOR HYDROCARBON AND SIMILAR FUEL

Filed Feb. 9, 1923

FIG. 1.

FIG. 2.

Robert Edwin Goldsbrough
INVENTOR:

By *Attoleman*
his Attorney

UNITED STATES PATENT OFFICE.

ROBERT EDWIN GOLDSBROUGH, OF CONSETT, ENGLAND.

BURNER FOR HYDROCARBON AND SIMILAR FUEL.

Application filed February 9, 1923, Serial No. 617,986, and in Great Britain February 16, 1922.

This invention relates to burners for hydrocarbon and similar fuel.

According to this invention, the fuel is atomized by steam and the mixture of fuel and steam is then raised to a high temperature whereupon decomposition takes place and a fixed gas, or a mixture of fixed gases, is produced.

In carrying out this invention, I employ two chambers into one of which the mixture is supplied, gasified therein, and introduced into the other chamber for combustion, the heat of the combustion being utilized to heat the chamber whereto the mixture is supplied in order to produce fixed gases by the reaction of the steam and fuel. By this means deposit of carbon from the fuel in the chamber to which the fuel is supplied may, by suitably varying the conditions of the reaction, be avoided.

By way of example, I will fully describe, with reference to the accompanying drawings, a vapor burner according to my invention applied to the fire flue of a Lancashire or like boiler, it being understood that my invention is not limited to this application.

In the drawings:—

Figure 1 is a longitudinal section, and,

Figure 2 is a plan, to a larger scale, of the mixing chamber.

Referring to the drawings, in the example therein illustrated, *a* is the fuel-and-steam mixture conduit which constitutes the one chamber and is formed by an outer casing *b* surrounding a spiral flange *c* around the exterior of a cast iron barrel *d* serving as the other chamber. The casing *b* is attached to a plate *e* closing the front of the fire flue *f* of the boiler, and a cowl *g* is provided which has openings *h* controlled by a revoluble shutter *j* whereby the admission of air to the interior of the barrel *d* can be regulated. Steam is supplied to a mixing chamber *k* through a pipe *m* controlled by a valve *n* and terminating in nozzles *p*, the centre one of which is separately controlled by a valve *q*. Liquid fuel is supplied to the mixing chamber *k* through a pipe *r* controlled by a valve *s* and terminating in nozzles *t* in the way of the jets of steam issuing from the side nozzles *p*. There is no fuel nozzle in the way of the centre steam jet *p*. The valve *u* controls the main steam supply, the jets *p* being atomizers for the fuel and

acting as auxiliary supplies of steam. By providing the centre nozzle *p* with a separate valve *q*, the main steam supply can be regulated for all pressures, and it is not opened until the conduit *a* has been heated to redness. The mixing chamber *k* communicates with the outer end of the conduit *a*. The other end of the conduit communicates at *u* with a pipe *v* leading through a valve *w* to a burner *y* disposed centrally of the barrel *d*, and, if desired, through a valve *w* to a storage reservoir or otherwise conveniently. While the barrel *d* is illustrated as being of slightly conical shape, this is not essential. However, it is found that by giving the inside bore of the barrel *d* a slight taper, the smaller diameter being at the open end, a gradation of temperature is obtained in the barrel which gives improved results. Insulation is or may be provided around the casing *b* as indicated at *z*.

It will be seen that, when the barrel *d* is red-hot, fuel supplied to the mixing chamber *k* is atomized by the steam jets from the nozzles *p* and intermingled with the steam, passes through the conduit *a*. While traversing the conduit *a* the particles of fuel are decomposed under the action of the heat and carbon is deposited upon the internal surface of the conduit while the freed hydrogen passes on. The deposited carbon becomes red-hot and combines with the oxygen of the superheated steam to form carbon-monoxide, the freed hydrogen of the steam passing on. The passage of the steam and fuel through the conduit *a* converts them into a mixture of carbon monoxide and hydrogen which, when burnt, produces a hot smokeless flame. The gaseous mixture leaves the conduit by the pipe *v* and it, or some of it, is used to feed the burner *y* in the barrel *d* whereby the combustion is effected and the barrel is kept red-hot.

The length of the conduit *a* and the proportions of steam and fuel supplied to the mixing chamber *k* are adjusted so that all the carbon deposited by the fuel in the conduit is taken up by the oxygen of the superheated steam and no residue is left in the conduit. I have found that satisfactory results can be obtained with a barrel of six inch bore and fifteen inches long with a half-inch square conduit of about twenty turns by using steam and fuel in the pro-

portion of about three pounds of fuel and nine pounds of water in the form of superheated steam. Preferably the pressure of the steam will be superposed on the fuel, there being no adverse effect from condensation occurring in the fuel reservoir. Should a carbon deposit accumulate in the conduit owing to too high a proportion of fuel being supplied to the mixing chamber *k*, the accumulation can be removed by shutting off the fuel and passing steam alone through the conduit, or, less rapidly, by increasing the proportion of steam to fuel supplied to the mixing chamber. When starting the burner, the conduit *a* may, if desired, be heated to red heat by previously produced gas from storage being burnt at the burner *y*, or rich gas, produced by opening the fuel and side steam nozzles *t* and *p*, may be passed through the conduit *a* and burnt at the burner *y* to heat the barrel *d* to redness.

Thus by my invention I provide an apparatus that will simultaneously produce gas and burn it on, what may be termed, a closed-circuit system, thus establishing a self-contained unit adapted for universal service.

If desired, air may be used as a substitute for, or as an adjunct to, the steam.

What I claim as my invention, and desire to secure by Letters Patent is:—

1. For producing gas from liquid hydrocarbons, apparatus comprising, in combination, a conduit, means for raising said conduit to a high temperature, and means for introducing the hydrocarbon and an atomizing fluid therefor into said conduit, said means including a mixing chamber positioned exteriorly of, but in communication with, the conduit, means for independently introducing said hydrocarbon into said mixing chamber, means for independently introducing said fluid into said chamber for atomizing said hydrocarbon, and means for independently introducing an additional supply of said fluid into said mixing chamber for commingling with the mixture of said atom-

ized hydrocarbon and of the fluid that atomized it.

2. A burner for hydrocarbon and similar fuel consisting of a self-contained unit comprising two concentrically-assembled shells constituting separate chambers with a common wall, the outer chamber being in the form of a coil, a mixing chamber connected to the front end of said outer chamber, means for separately supplying an atomizing fluid and fuel to said mixing chamber previous to introduction into the outer chamber the fuel being atomized by the fluid in the mixing chamber, said means comprising nozzles, some of which are closely adjacent, projecting into the mixing chamber and of which the nozzles for atomizing fluid are in preponderance and one is separately controlled and is not closely adjacent to a fuel nozzle, a burner within the inner chamber, means for conveying the gasified mixture produced in the outer chamber from the rear end thereof to said burner for combustion, and means for supplying air to said inner chamber, the heat of combustion being utilized to heat to a high temperature the outer chamber whereby the mixture of atomizing fluid and fuel therein is decomposed and a fixed gaseous product obtained.

3. For producing gas from liquid hydrocarbons, apparatus comprising, in combination, a conduit, means for raising said conduit to a high temperature, and means for introducing the hydrocarbon and an atomizing fluid therefor into said conduit as a combustible mixture, said means including a mixing chamber positioned exteriorly of, but in communication with, the conduit, means independently introducing said hydrocarbon and said fluid to produce at least two atomized jets of said mixture, and means for introducing an additional supply of said fluid as a single jet into said mixing chamber between said jets for commingling with them.

In testimony whereof I affix my signature.

ROBERT EDWIN GOLDSBROUGH.
